US00D391792S

United States Patent [19]

Scherer et al.

[11] Patent Number: Des. 391,792

[45] Date of Patent: **Mar. 10, 1998

[54] **PORTABLE, FOLDABLE BED RAIL**

[75] Inventors: **Craig S. Scherer, Wilmette; Michael C. Thuma, Desplaines; Ann-Marie Conrado, Chicago, all of Ill.**

[73] Assignee: **BRK Brands, Inc., Aurora, Ill.**

[**] Term: **14 Years**

[21] Appl. No.: **54,699**

[22] Filed: **May 20, 1996**

[51] LOC (6) Cl. **06-94**

[52] U.S. Cl. **D6/503**

[58] Field of Search **D6/503, 491; 5/424-426, 5/428, 512; D24/184**

Attorney, Agent, or Firm—Paul M. Vargo, Esq.

[57] **CLAIM**

The ornamental design for a portable, foldable bed rail, as shown and described.

DESCRIPTION

FIG. 1 is a front perspective view of a portable, foldable bed rail embodying the principles of the present invention, illustrated in the upright or operative position;

FIG. 2 is a rear perspective view of the portable, foldable bed rail of FIG. 1;

FIG. 3 is a front view of the bed rail of FIG. 1;

FIG. 4 is a rear view of the bed rail of FIG. 1;

FIG. 5 is a side view of the bed rail of FIG. 1, the opposite side being a mirror image thereof;

FIG. 6 is a top view of the bed rail of FIG. 1;

FIG. 7 is a front, perspective view of the bed rail of FIG. 1, illustrated in the downfolded position; and,

FIG. 8 is a perspective view of the bed rail of FIG. 1, illustrated in the folded state.
